DESIGN FOR A VACUUM CLEANER

Axel Albert Forsberg, Stora Essingen, Sweden

Application September 5, 1941, Serial No. 103,175

Term of patent 14 years

To all whom it may concern:

Be it known that I, Axel Albert Forsberg, a subject of the King of Sweden and a resident of Stora Essingen, Sweden, have invented a new, original, and ornamental Design for Vacuum Cleaners, of which the following is a specification, reference being had to the accompanying drawings, forming a part thereof and of which:

Fig. 1 is a perspective view showing a side and the top of a vacuum cleaner embodying my new design;

Fig. 2 is a perspective view showing a side, the rear and the top of the vacuum cleaner illustrated in Fig. 1;

Fig. 3 is a perspective view showing a side, the front end and the top of the vacuum cleaner;

Fig. 4 is a perspective view showing the rear end and the top of the vacuum cleaner; and

Fig. 5 is a perspective view showing the front end and the top of the vacuum cleaner illustrated in the preceding figures.

I claim:

The ornamental design for a vacuum cleaner, as shown.

AXEL ALBERT FORSBERG.
